UNITED STATES PATENT OFFICE.

GEORGE E. BOWER, OF AUBURN, NEW YORK, ASSIGNOR OF ONE-HALF TO
JOHN H. LYNCH, OF SAME PLACE.

CHECK-CASE.

SPECIFICATION forming part of Letters Patent No. 388,251, dated August 21, 1883.
Application filed January 11, 1888. Serial No. 260,393. (No model.)

To all whom it may concern.

Be it known that I, GEORGE E. BOWER, of the city of Auburn, New York, have invented certain new and useful Improvements in 5 Check-Cases, of which the following is a description, reference being had to the accompanying drawings, in which—

Figure 1 is a front view; and Figs. 2 and 3 are side and top views, respectively.

10 My invention relates to cases for holding checks; and it consists in a novel construction of such cases, by means of which a number of the aforesaid checks are successively brought into position to be grasped and removed from 15 the case, while only a single check can be thus grasped and removed at one time.

I construct my check-case in the following manner: Within a frame, A, and secured upon a suitable back, B, I place the inclined ways 20 C C C C C, which are made, as shown, in portions, which are combined to form a zigzag course or track, all within one vertical plane. The checks which I prefer to use are flat circular plates or disks of any suitable material, 25 although this form is not essential. The ways C C are channeled to retain the checks by means of their projecting sides d d, while a cover of glass or other suitable material prevents the checks from falling forward. The extremities 30 of the different sections of the zigzag track C C are joined to make it afford a continuous pas-

sage for the descent by gravity of the checks, as shown. The upper end of the track C is provided with a suitably-enlarged mouth or hopper, E, for convenient insertion of the 35 checks, while the lower end of said track C is provided with a receiver or cup, G, formed to receive and hold a single check, e, at a time while the sides thereof are cut out, as shown at g, to afford a better grasp upon the check 40 therein.

A slide, H, may be pushed down, when desired, to cover the lower extremity of the track C, and thus prevent the checks from descending into the cup G.

Having thus described my invention, what I 45 claim as new, and desire to secure by Letters Patent, is—

In a check-case, the vertical zigzag inclosed track C C, formed of the channeled strips d 50 d, and provided with a cover to retain the checks from falling forward, in combination with an external fixed receiver, G, adapted to hold one check at a time, said receiver extending upward at the back of the check to its 55 middle point, and provided with the recesses g in its sides to enable the check to be grasped, substantially as described.

GEORGE E. BOWER.
